UNITED STATES PATENT OFFICE.

MICHAEL R. KELLY, OF TROY, NEW YORK, ASSIGNOR OF ONE-HALF TO CATHERINE L. MARTIN, OF TROY, NEW YORK.

NECKBAND.

Application filed June 6, 1922. Serial No. 566,235.

To all whom it may concern:

Be it known that I, MICHAEL R. KELLY, a citizen of the United States, and a resident of Troy, in the county of Rensselaer and State of New York, have invented a new and Improved Neckband, of which the following is a full, clear, and exact description.

This invention relates to improvements in neckbands, an object of the invention being 10 to provide a neckband which can be formed from a single blank, which will provide a plurality of folds to ease the collar button against the neck, and which will provide a minimum of thicknesses at the upper edge 15 of the band so that the band will be comfortable to the user.

A further object is to provide a neckband of the character stated, which can be manufactured and sold at a reasonably low price 20 and which will embody the maximum of wearing qualities and comfort to the user.

With these and other objects in view, the invention consists in certain novel features of construction and combinations, and arrangement of parts, as will be more fully hereinafter described and pointed out in the claims.

In the accompanying drawings—

Figure 1 is a view in elevation of my 30 improved neckband.

Figure 2 is a view in longitudinal section on the line 2—2 of Figure 1, the thicknesses of material being greatly exaggerated for clearness.

Figure 3 is a view in transverse section on the line 3—3, of Figure 1.

Figure 4 is a view in transverse section on the line 4—4, of Figure 1.

Figure 5 is a plan view of the blank from 40 which my improved neckband is made.

In constructing my improved neckband, I first provide a blank A, as indicated in Figure 5. This blank is of linen, cotton or any other suitable relatively thin and 45 strong fabric, and its longitudinal outer edges are preferably slightly curved as shown, and the V shaped recesses 1 are formed in the center of the ends and extend inwardly to a pair of transverse slits 2, 2 50 respectively. The material B, between the

slits, constitutes a reinforcement and is folded on the lines 3, 4 and 5 as clearly indicated in Figure 4. The main sections of the blank are folded on longitudinal lines 6 and 7 respectively.

When the blank is folded on the lines 6, 55 3, 4, 5 and 7, it will take the shape shown in Figures 3 and 4, when the outer upper edges are turned inwardly and secured by a line of stitching 8, the dotted lines in Figure 5 indicating where the stitching takes place.

It will be noted that while I provide 60 a 6 ply structure at the intermediate portion of the band with the button hole 9 extending through the two outer thicknesses, and the four inner thicknesses constituting a backing for the button to render it comfortable to the wearer, and to insure strength and durability, however, notwithstanding 65 such a reinforced structure, it will be noted that the upper edge of the band is relatively thin and flexible so that it will be comfortable to the neck of the user, and while in Figures 1, 3 and 4, the structure appears 70 somewhat thick because of the exaggeration in drawings, in the actual device where thin material is employed, the edge will be thin 75 and flexible.

Various slight changes might be made in 80 the general form and arrangement of parts described without departing from my invention, and hence I do not limit myself to the precise details set forth, but consider myself at liberty to make such changes and 85 alterations as fairly fall within the spirit and scope of the appended claims.

I claim:

1. A neck band formed from a single piece of material having plain unobstructed 90 longitudinal edges and provided on each side of its center of length and at a distance therefrom with a transverse slit extending beyond the center of width of the material, the material being folded longitudinally 95 at each side of the center of width and at the center of width, whereby the folded portions will overlie one another and the portion between the slits folded to lie between and depend from the said folded por- 100

tions, the upper longitudinal edges and ends of the folded overlying portions being turned in and stitched together, the outermost one of which is provided with button holes.

2. A neckband blank having curved longitudinal edges and provided in its end

with central longitudinal V-shaped notches terminating at a distance from the center of length of the blank and at the inner ends of the said notches with transverse slits extending on each side of the center of width of the blank.

MICHAEL R. KELLY.
